ICE CREEPER

Fern Mong, Greenville, Ohio

Application March 24, 1934, Serial No. 717,207

4 Claims. (Cl. 36—7.6)

This invention relates to a device designed to be positioned over the sole of a shoe or boot, the device being provided with means to bite into ice or other slippery surfaces to insure against the person using the device slipping while walking over such surfaces.

An important object of the invention is to provide a device of this character which may be used by firemen or carpenters while standing or walking over slippery roofs of buildings, the device affording means to prevent slipping of the user.

A still further object of the invention is to provide a device of this character which may be adjusted to various widths and lengths, adapting the device for use on boots and shoes of various sizes.

Another object of the invention is to provide a device of this character which may be readily and easily secured on the foot of the user, in such a way as to insure against displacement of the device, while in use.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

Referring to the drawings:

Figure 1 is a bottom plan view of a creeper constructed in accordance with the invention.

Figure 2 is a sectional view taken on line 2—2 of Figure 1.

Figure 3 is a side elevational view of the creeper.

Figure 4 is a sectional view taken on line 4—4 of Figure 1.

Referring to the drawings in detail, the device comprises a heel section 5 and a toe section 6, the heel section comprising a wide heel engaging portion 7 and a forwardly projecting portion 8 adapted to engage under the instep of the boot or shoe to which the device is secured.

This forwardly projecting section 8 is formed with an elongated opening 9 that extends throughout the entire length of the section 8, the lower surface of the forwardly projecting surface being provided with teeth 10, for purposes to be hereinafter more fully described.

Ears 11 extend upwardly from the heel engaging portion 7 of the heel section, and afford

means whereby the strap 12 is secured to the heel section 5, the strap 12 being of a construction to engage over the instep of the user, securing the heel section in position.

Extending downwardly from the bottom of the heel engaging portion 7, are spikes 13, which spikes may be secured in the heel engaging portion 7, by rivets or other suitable means.

The toe section comprises members 14 which are wide at their forward ends, and of lengths 10 to extend an appreciable distance over the forwardly projecting section 8 of the heel section 5, when the toe section is secured to the heel section 5, thereby providing for an adjustment of the sections with respect to each other, to lengthen or shorten the device.

As shown, these members 14 have their inner ends connected by means of the bolt 15, so that pivotal movement of the members 14 will be permitted, allowing the wide forward ends of the 20 members 14, to be moved towards or away from each other so that the toe section may be adjusted laterally and positioned on boots or shoes of various widths.

Secured to the toe section, by means of the 25 bolt 15 is a washer 16, which washer is formed with teeth on its upper surface, which teeth cooperate with the teeth 10 of the forwardly projecting section 8, holding the heel section and toe section against movement with respect to each 30 other, after an adjustment has been made. A nut 17 is positioned on the bolt 15, and is adapted to clamp the heel section and toe section together.

Pivots secured to one of the members 14 of 35 the toe section, by means of the bolt 24, is a bar 18, which bar is formed with an elongated opening 19 disposed near the free end thereof, which bar is adapted to accommodate the bolt 20 that extends from the adjacent member 14, 40 there being provided a nut 21 on the bolt 20 engaging and securing the bar 18 in its positions of adjustment.

The reference character 26 designates a washer positioned on the bolt 20, the washer having teeth 45 adapted to cooperate with the teeth 27 of the bar 18, holding the bar and toe members, against lateral movement, after an adjustment has been made.

Spikes indicated by the reference character 22 50 extend downwardly from the members 14 of the toe section, and are adapted to bite into the surface on which the device is being used, preventing slipping.

In order that the person's foot on which the 55

device is secured, will be held against lateral movement, metallic foot engaging members 23 are provided, which members 23 are made integral with the members 14 of the toe section, 5 and curve upwardly and inwardly from the upper surfaces thereof. These members 23 also provide members to which the straps 25 are secured, which straps secure the toe section of the creeper to the foot of the user.

10 From the foregoing it will be seen that due to the construction shown and described, the device may be readily and easily positioned over a boot or shoe, and readily adjusted so that it will properly fit such boot or shoe.

15 After the straps have been secured around the boot or shoe of the user, the creeper will be held against displacement and the person using the device may walk over icy or slippery surfaces without danger of slipping.

20 Having thus described the invention, what is claimed is:

1. In an ice creeper, a heel section having an elongated opening and having teeth formed on the lower side thereof, a toe section embodying laterally adjustable members, a bolt pivotally connecting the members, a washer on the bolt and having teeth adapted to engage the teeth of the heel section when the bolt is secured in position, holding the heel and toe sections in their 30 positions of adjustment.

2. In an ice creeper, a heel section, said heel section having an elongated opening, a toe section comprising laterally adjustable members, a bolt pivotally connecting the laterally adjustable members, said bolt passing through the elongated opening and adapted to secure the heel section

and toe section together, whereby the sections may be adjusted to lengthen or shorten the creeper, and means for securing the members forming the toe section in the positions of their adjustment.

3. In an ice creeper, a heel section and a toe section, a forwardly projecting narrow section forming a part of the heel section and having an elongated opening, teeth formed on the lower surface of the forwardly projecting section, said toe section comprising a pair of laterally adjustable members, a bolt pivotally connecting the members at their inner ends, said bolt extending through the elongated opening, a washer having teeth mounted on the bolt, said bolt adapted to exert pressure on the washer, whereby the teeth of the washer are brought into engagement with the teeth of the forwardly projecting section, holding the heel section and toe section together, and spikes extending from the heel section and toe section.

4. An ice creeper comprising a heel section and a toe section, said heel section having an elongated opening, means for pivotally connecting the sections, said means including a bolt carried by the toe section and disposed within the elongated opening whereby the creeper may be lengthened or shortened, said toe section comprising pivotally connected members, a bar connecting the members of the toe section, and means for adjustably securing the bar to one of the members of the toe section whereby the members of the toe section are held in various positions of adjustment.
